UNITED STATES PATENT OFFICE

120,527

DESIGN FOR A COMBINATION LAMP AND MIRROR OR SIMILAR ARTICLE

Harry B. Gross, Brooklyn, N. Y.

Application March 8, 1940, Serial No. 90,770

Term of patent 3½ years

To all whom it may concern:

Be it known that I, Harry B. Gross, a citizen of the United States of America and a resident of the Borough of Brooklyn, city of New York, Kings County, and State of New York, have invented a new, original, and ornamental Design for a Combination Lamp and Mirror or Similar Article, of which the following is a specification, reference being had to the accompanying drawing, forming a part thereof.

In the drawing:

Figure 1 is a view in perspective of a combination lamp and mirror or similar article showing my new design. In this view the lamp and mirror portions are tilted with relation to the base portion.

Figure 2 is a front elevational view of the com-

bination lamp and mirror or similar article shown in Figure 1 with the mirror and lamp portions adjusted to a vertical position with relation to the base.

Figure 3 is a rear elevation view of Figure 2.

Figure 4 is a side elevational view of the combination lamp and mirror, shown in Figure 2, as might be seen from the right side thereof, with the exception that the magnifying mirror element thereof is shown in an elevated position.

Figure 5 is a plan view of Figure 2.

I claim:

The ornamental design for a combination lamp and mirror or similar article, as shown and described.

HARRY B. GROSS.
